DESIGN FOR A PNEUMATIC TIRE

Pierre Marcel Bourdon, Paris, France, assignor
to Michelin & Cie, Clermont-Ferrand, France,
a corporation of France

Original No. 97,255, dated October 22, 1935, Serial
No. 56,220, April 5, 1935, for 7 years. Application
for reissue February 13, 1936, Serial No.
61,141. Term of patent 7 years

To all whom it may concern:

Be it known that I, Pierre Marcel Bourdon, a citizen of the French Republic and a resident of Paris, France, have invented a new, original, and ornamental Design for a Pneumatic Tire, of which the following is a specification, reference being had to the accompanying drawing, forming a part thereof.

Figure 1 is a fragmentary perspective view of a pneumatic tire, showing my new design.

Figure 2 is a fragmentary top plan view.

I claim:

The ornamental design for a pneumatic tire as shown.

PIERRE MARCEL BOURDON.
